UNITED STATES PATENT OFFICE.

FRANK T. SWEIGART, OF CHICAGO, ILLINOIS.

PHONOGRAPH REPEATER.

Application filed May 1, 1920. Serial No. 378,075.

To all whom it may concern:

Be it known that I, FRANK T. SWEIGART, a citizen of the United States, residing at Chicago, in the county of Cook and State 5 of Illinois, have invented a certain new and useful Improvement in Phonograph Repeaters (Case 1), of which the following is a full, clear, concise, and exact description, reference being had to the accompanying 10 drawings, forming a part of this specification.

My invention relates to improvements in phonograph repeaters, and is especially concerned with the provision of means 15 whereby an ordinary disk record can be repeatedly played with substantially no delay between the reproductions.

The objects of my invention are:

1st. To provide a repeating mechanism 20 which is entirely automatic in its operation.

2nd. To provide a repeating mechanism comprising two reproducers and means for alternately bringing these reproducers into 25 the proper co-acting relation with the beginning of the sound groove in a phonograph record, whereby the record can be repeatedly reproduced without interruption.

3rd. To provide a repeating mechanism 30 of the character described which can be quickly and easily adjusted to repeat records of any size; and

4th. To provide a repeating mechanism 35 of the character described which is simple in construction, economical to manufacture, easy to operate and reliable.

Other objects will appear as this description progresses, reference being had to the accompanying drawings in which

40 Figure 1 is a plan view of a phonograph embodying my repeating mechanism, portions thereof being broken away showing one of the reproducers in contact with the record;

45 Figure 2 is a fragmentary plan view showing the position of certain portions of the mechanism when the other reproducer is in contact with the record;

50 Figure 3 is a side elevation of my improved mechanism;

Figure 4 is an enlarged sectional detail, portions of the mechanism being broken away;

55 Figure 5 is a vertical, transverse section taken on line 5—5 of Figure 1;

Figure 6 is a horizontal section taken substantially on line 6—6 of Figure 4;

Figure 7 is a plan view showing a modified embodiment of my invention; and

Figure 8 is a side elevation of one of the reproducers used in the construction shown in Figure 7.

Referring for the present to Figures 1 to 6, inclusive, the reference character 10 indicates the motor board of a phonograph 65 which may be of any desired construction and upon which is rotatably mounted the turn table 11. My invention is not in any way concerned with the details of construction of the means for rotating the turn 70 table 11 and I have consequently omitted illustration of the motor for driving the same. A disc record 12 is shown on the turn table.

I shall now describe the details of construction of the means by which I can repeatedly reproduce a record substantially 75 without interruption. A sleeve 13 having the flange 14 extended from the upper side thereof is rotatably mounted in the motor 80 board and its lower end communicates with the amplifier 15 which may be of any suitable construction. A tubular member 16 is rotatably mounted in the sleeve 13 and is provided with a transversely extending 85 head 17 which forms a horizontal bearing for the lower end of a second tubular member 17', the lower end of which is provided with a cylindrical transverse journal 18 which is rotatably mounted in the transverse 90 bearing 17 of the tubular member 16. The tubular member 17 comprises a horizontal extension 19 on which is rotatably mounted the horizontal portion 20 of the elbow 21. The vertical portion 22 of the elbow 21 ex- 95 tends upwardly and is transversely enlarged to provide two spaced bearings for the vertically extending bearing portions 23 of the tone arms 24 and 24', these tone arms being provided with flanges 25 bearing 100 on the upper end of the elbow 21. A set screw 26 secured in the extension 19 of the tubular member 17 co-acts with the ends of a slot 27 formed in the lower side of the horizontal portion 20 of the elbow 21 to 105 limit the extent of rotation of the elbow around the horizontal extension 19.

The free ends of each of the tone arms 24 and 24' are provided with reproducers 29 and 30, respectively, the needle supporting 110

levers 31 and 32 of which are inclined in opposite directions in order to hold the needles in proper relation to the surface of the record. The tone arms 24 and 24' are supported at such a distance above the record that in order to bring the needle of either reproducer into contact with the record, it is necessary to tilt the elbow 21 on the horizontal extension 19 (see Figures 3 and 5). At the same time this tilting movement lifts the other reproducer from the record. In both Figures 3 and 5, the distance of the tone arms from the record and the degree of tilting are considerably exaggerated for in actual practice when the needle of one reproducer is in contact with the record, the needle of the other reproducer will be spaced from the record only a small fraction of an inch. It will be noted from an inspection of Figure 1 that the angular relation between the two tone arms 24 and 24' is such that at the instant the needle of the receiver 30 is lifted out of contact with the end of the sound groove and the record, the needle of the reproducer 29 is brought into contact with the beginning of the sound groove of the record. To make the repeated reproduction of the record continuous, it is necessary to provide means for alternately bringing the needles of the two reproducers into contact with the beginning of the sound groove. For this purpose I provide the lever 35 which is pivoted to the top of the tubular member 17 by means of a screw 36 so that the lever 35 can rotate about a substantially vertical axis. A slot 37 is formed intermediate the ends of the lever and co-acts with a pin 38 secured to the upper portion of the horizontal part of the elbow 21. The flange 14 is provided at its rear side with a vertical stud 39. A tension spring 40 connects the upper end of the stud 39 and a pin 41 projecting from the free end of the lever 35. From the above description it will be clear that as long as the axis of the spring 40 lies upon the side of the pivot screw 36, shown in Figure 1, this spring will tend to rotate the lever 35 in a clockwise direction and will thus cause the elbow 21 to tilt so as to hold the needle of the reproducer 29 in contact with the record. As the record rotates, however, the reproducer 29 will move toward the center of the record, thereby causing the lever 35 to move in a counter-clockwise direction and at the same time placing the spring 40 under slightly increased tension. The axis of the spring 40 will also be moved in a counter-clockwise direction until it passes over the center of the pivot screw 36, whereupon the tension of the spring will operate to draw the lever 35 in a counter-clockwise direction and thus through the pin and slot connection rotate the elbow 21 about its horizontal axis in the proper direction to bring the needle of the reproducer 30 into contact with the record. It will be

clear that if the two tone arms 24 and 24' are properly spaced from each other, the needle of the reproducer 30 will be brought into contact with the beginning of the sound groove of the record at the same time that the needle of the reproducer 29 is lifted from the end of the sound groove.

In order to adjust my improved repeating mechanism to records of varying diameter, I provide means for rotating the flange 14 about the axis of the sleeve 13, whereby the position of the stud 39 relative to the pivot pin 36 can be varied so as to vary the intervals between the tiltings of the elbow 21 and thereby compensating for records of varying diameter.

It will, of course, be clear that when the needle of the reproducer 29 has been lifted from the record and the needle of the reproducer 30 has been brought into contact with the beginning of the record upon continued rotation of the record the two tone arms will be moved in a counter-clockwise direction, thereby again placing the spring 40 under tension and moving it and the lever 35 in a clockwise direction until a point is reached where the axis of the spring 40 is moved past the center of the pivot screw 36 in the opposite direction from that described above, whereupon the elbow 21 will again be tilted about its horizontal axis but in the opposite direction, whereupon the needle of the reproducer 29 will be brought into contact with the beginning of the sound groove. This action continues indefinitely as long as the record is rotated, thereby making it possible to repeatedly reproduce the record with substantially no interruption between the separate reproductions.

For rotating the sleeve 13 and the flange 14 in order to vary the position of the stud 39, I provide the edge of the flange with a gear segment 45 which is adapted to mesh with the gear segment 46 carried by the lever 47, which is pivoted to the motor board at 48. The lever 47 is provided with a reversely curved portion 49 for clearing the turn table shaft 50. By adjusting the lever 47 about its pivot point 48 the angular position of the stud 39 can be varied as desired.

The annular space occupied by the sound groove varies in width on different records. It is, therefore, necessary to make the tone arms 24 and 24' adjustable angularly with respect to each other to compensate for these differences and to hold the tone arms in their adjusted positions. It is also necessary for the proper operation of my apparatus that in any of their adjusted positions, each tone arm shall be equally angularly displaced from an imaginary line through the axis of the horizontal extension 19' of the tubular member 17.

I have previously described the bearing portions 23 of the tone arms as being rotat-

ably mounted in the upper end 22 of the elbow 21, whereby the two tone arms can be adjusted angularly of each other. In order to insure the equal displacement of the tone arms relatively to the imaginary line referred to above, I provide the edges of the flanges 25 with the inter-meshing gear segments 53 and 54. For securing the two tone arms in their adjusted position, I secure the slotted segments 55 and 56 to the tone arms 24 and 24', respectively. A thumb screw 57 may be used for securing these segments in their adjusted positions.

By the proper operation of my repeating mechanism, it is necessary that the ends of the needles of the two reproducers shall engage with the record which describes arcs of equal length. Since the two needles are inclined in opposite directions, this means that it is necessary to lengthen the tone arm 24, as shown in Figure 1. I can accomplish this same result with tone arms of equal length, as shown in Figures 7 and 8, by changing the angle of inclination of the needle lever 31 and providing it with a needle clamping means 60 which inclines in a direction opposite to the inclination of the needle lever 31 (see Figure 8).

While I have described the details of the preferred embodiments of my invention, it is to be clearly understood that my invention is not to be limited to these details, but is capable of other adaptations and modifications within the scope of the appended claims. Furthermore, it is to be clearly understood that wherever in the specification and claims the words vertical, horizontal, clockwise, counter-clockwise and other words indicating direction are used, these terms are merely relative and are not used in their concrete sense.

Having thus described my invention, what I claim is:

1. In a phonograph, the combination of a motor board, a sleeve rotatably mounted on said motor board and provided with an outwardly extending flange having a stud extending upwardly therefrom, a tubular member mounted on said sleeve to rotate about a vertical axis, a second tubular member communicating with said first-named tubular member and pivotally mounted thereon to rotate about a horizontal axis, said second tubular member having a horizontal extension, an elbow having one end rotatably mounted on said horizontal extension, a pair of tone arms communicating with the other end of said elbow and pivotally mounted thereon to rotate about a vertical axis, the said tone arms being angularly adjustable relatively to each other, means for insuring an equal angular displacement of said tone arms with respect to the horizontal axis of said second tubular member, means for maintaining said tone arms in their adjusted position, a lever having one end pivotally mounted on said second tubular member to rotate about a vertical axis, a loose connection between an intermediate portion of said lever and said elbow, a spring connecting the free end of said lever and the upper end of said stud, and means for adjusting said sleeve about its axis.
2. In a phonograph, the combination of a motor board, a sleeve rotatably mounted on said motor board and provided with a stud extending upwardly therefrom, a tubular member mounted on said sleeve to rotate about a vertical axis, a second tubular member communicating with said first-named tubular member and pivotally mounted thereon to rotate about a horizontal axis, said second tubular member having a horizontal extension, an elbow having one end rotatably mounted on said horizontal extension, a pair of tone arms communicating with the other end of said elbow and pivotally mounted thereon to rotate about a vertical axis, the said tone arms being angularly adjustable relatively to each other, means for maintaining said tone arms in their adjusted position, a lever having one end pivotally mounted on said second tubular member to rotate about a vertical axis, a loose connection between an intermediate portion of said lever and said elbow, a spring connecting the free end of said lever and the upper end of said stud, and means for adjusting said sleeve about its axis.
3. In a phonograph, the combination of a motor board, a sleeve rotatably mounted on said motor board and provided with a tubular member mounted on said sleeve to rotate about a vertical axis, a second tubular member communicating with said first-named tubular member and pivotally mounted thereon to rotate about a horizontal axis, said second tubular member having a horizontal extension, an elbow having one end rotatably mounted on said horizontal extension, a pair of tone arms communicating with the other end of said elbow and pivotally mounted thereon to rotate about a vertical axis, the said tone arms being angularly adjustable relatively to each other, means for maintaining said tone arms in their adjusted position, a lever having one end pivotally mounted on said second tubular member to rotate about a vertical axis, a loose connection between an intermediate portion of said lever and said elbow, a spring connecting the free end of said lever and the upper end of said stud, and means for adjusting said sleeve about its axis.
4. In a phonograph, the combination with a pair of tone arms, of means for supporting said tone arms to rotate about parallel vertical axes, means whereby the angular displacement of said tone arms relative to each other can be adjusted and maintained, and means for automatically rotating said tone arms about a horizontal axis.
5. The combination with a record, of means for rotating said record, a pair of re-

- producers for respectively engaging said record on opposite sides of its center, and means energized by the movement of one of said reproducers toward the center of said record, and prior to any movement of said reproducer away from said record, for lifting said reproducer from said record and placing the other reproducer in contact with said record.
10. 6. The combination with a record, of means for rotating said record, a pair of reproducers, and spring means energized by the movement of one of said reproducers for instantaneously lifting said last-named reproducer from said record and lowering the other reproducer into contact with said record.
7. The combination with a record, of means for rotating said record, a pair of reproducers, and spring means for lifting one of said reproducers from said record and lowering the other reproducer into contact with said record.
8. The combination with a record, of means for rotating said record, a pair of reproducers, and means energized by said rotating means for instantaneously lifting one of said reproducers from the end of the record groove and substantially simultaneously engaging the other reproducer with the beginning of said record groove.
9. A phonograph comprising a pair of reproducers, means for supporting said reproducers in spaced relation, means for adjusting the spacing of said reproducers,
- means for causing said reproducers to swing about a common axis in traversing a record, said axis being substantially perpendicular to the line of travel of said reproducers to alternately bring said reproducers into contact with the beginning of a record.
10. A phonograph comprising a pair of reproducers, means for supporting said reproducers in spaced relation, and means for lifting one of said reproducers from the end of the record groove and substantially simultaneously engaging the other reproducer with the beginning of said record groove comprising a spring tensioned by the movement of said reproducers, and adjustable means for determining when said spring is to act to change the position of said reproducers.
11. A phonograph comprising a pair of reproducers adapted alternately to be brought into engagement with the record groove of a record, a spring energized by the movement of one of said reproducers for automatically lifting said reproducer from the record when the reproducer has reached the end of the record and substantially simultaneously bringing the other reproducer into engagement with the beginning of the record groove.

In witness whereof, I hereunto subscribe my name this 28th day of April, 1920.

FRANK T. SWEIGART.
